United States Patent Office

Des. 203,485
Patented Jan. 11, 1966

203,485

BUOY

Charles E. Shepherd, P.O. Box 9445, Houston, Tex.
Filed Mar. 10, 1965, Ser. No. 84,172

Term of patent 14 years

(Cl. D71—1)

FIG. 1 is a front elevational view of a buoy embodying my new design;

FIG. 2 is a top plan view thereof;

FIG. 3 is a bottom plan view thereof; and,

FIG. 4 is a side elevational view thereof.

I claim:

The ornamental design for a buoy, substantially as shown and described.
